TOY STOVE

Martin L. Blumenthal, Summit, N.J., assignor to De Luxe Reading Corporation, a corporation of New Jersey

Filed Mar. 7, 1966, Ser. No. 1,324

Term of patent 7 years

(Cl. D34—15)

FIG. 1

FIG. 4

FIG. 2

FIG. 3

FIG. 1 is a top plan view of a toy stove showing my new design;

FIG. 2 is a front elevational view of the stove;

FIG. 3 is a side elevational view of the stove; and

FIG. 4 is a fragmentary horizontal cross-sectional view of the instrument panel of the stove taken on line 4—4 of FIG. 2.

I claim:

The ornamental design for a toy stove, as shown.
